[57] CLAIM

The ornamental design for a sponge and squeegee combination, as shown and described.

DESCRIPTION

FIG. 1 is an end elevational view of a sponge and squeegee combination showing my new design;

FIG. 2 is a top plan view of thereof; and,

FIG. 3 is a perspective view thereof as seen from the top, one side, and the end opposite that shown in FIG. 1.

The undisclosed side is the same in appearance as the side shown in FIG. 3, and the bottom of the sponge is flat.

FIG. 1

FIG. 2

FIG. 3
